UNITED STATES PATENT OFFICE

96,749

DESIGN FOR A BRUSH FOR DENTAL PLATES

Victor Hellonen, Detroit, Mich., assignor of one-half to Carl W. Soderblom, Detroit, Mich.

Application July 3, 1935, Serial No. 57,509

Term of patent 14 years

To all whom it may concern:

Be it known that I, Victor Hellonen, a citizen of the United States, residing at Detroit, in the county of Wayne and State of Michigan, have invented a new, original, and ornamental Design for a Brush for Dental Plates, of which the following is a specification, reference being had to the accompanying drawing, forming a part hereof, in which

I claim:

The ornamental design for a brush for dental plates, as shown.

VICTOR HELLOUNEN.
